US00D842938S

(12) **United States Design Patent** (10) **Patent No.:** **US D842,938 S**
(45) **Date of Patent:** **** Mar. 12, 2019**

(54) **FIGURINE**

(71) Applicant: **Mattel-MEGA Holdings (US), LLC**,
El Segundo, CA (US)

(72) Inventors: **Benoit Vézina**, Montreal (CA); **Eric Perreault**, St Basile le Grand (CA)

(73) Assignee: **Mattel-MEGA Holdings (US), LLC**,
El Segundo, CA (US)

(**) Term: **15 Years**

(21) Appl. No.: **29/611,338**

(22) Filed: **Jul. 20, 2017**

(51) LOC (11) Cl. **21-03**

(52) U.S. Cl.

USPC **D21/661**

(58) **Field of Classification Search**

(57) **CLAIM**

The ornamental design for a figurine, as shown and described.

DESCRIPTION

FIG. 1 is a top front isometric perspective view of a first embodiment of a figurine showing the new design; FIG. 2 is a top back isometric perspective view thereof;

FIG. 3 is a front elevational view thereof;

FIG. 4 is a rear elevational view thereof;

FIG. 5 is a side elevational view thereof;

FIG. 6 is an opposite side elevational view thereof;

FIG. 7 is a top plan view thereof;

FIG. 8 is a bottom plan view thereof; FIG. 9 is a top front isometric perspective view of a second embodiment of a figurine showing the new design;

FIG. 10 is a top back isometric perspective view thereof;

FIG. 11 is a front elevational view thereof;

FIG. 12 is a rear elevational view thereof;

FIG. 13 is a side elevational view thereof;

FIG. 14 is an opposite side elevational view thereof;

FIG. 15 is a top plan view thereof;

FIG. 16 is a bottom plan view thereof;

FIG. 17 is a top front isometric perspective view of a third embodiment of a figurine showing the new design;

FIG. 18 is a top back isometric perspective view thereof;

FIG. 19 is a front elevational view thereof;

FIG. 20 is a rear elevational view thereof;

FIG. 21 is a side elevational view thereof;

FIG. 22 is an opposite side elevational view thereof;

FIG. 23 is a top plan view thereof; and,

FIG. 24 is a bottom plan view thereof.

The broken lines and unshaded areas form no part of the claimed design. The various directional adjectives used in this specification, such as "front," "rear," "side," "top," and "bottom," refer to the figurine as illustrated.

1 Claim, 24 Drawing Sheets
